UNITED STATES PATENT OFFICE.

MARTIN WARNKE, OF MINNEAPOLIS, MINNESOTA.

COIN-CONTROLLED VENDING-MACHINE.

SPECIFICATION forming part of Letters Patent No. 780,628, dated January 24, 1905.

Application filed June 25, 1904. Serial No. 214,202.

To all whom it may concern:

Be it known that I, MARTIN WARNKE, a citizen of the United States, residing at Minneapolis, in the county of Hennepin and State of Minnesota, have invented certain new and useful Improvements in Coin-Controlled Vending-Machines; and I do hereby declare the following to be a full, clear, and exact description of the invention, such as will enable others skilled in the art to which it appertains to make and use the same.

My invention relates to vending-machines such as are controlled by deposited coin, and has for its object to improve the same in the several particulars hereinafter noted.

The invention consists of the novel devices and combinations of devices hereinafter described, and defined in the claims.

The invention is illustrated in the accompanying drawings, wherein like characters indicate like parts throughout the several views.

Figure 1 is a view in front elevation, showing the vending-machine embodying the features of my invention. Fig. 2 is a vertical section taken from front to rear of the machine on the line $x^2 x^2$ of Fig. 1. Fig. 3 is a horizontal section taken approximately on the line $x^3 x^3$ of Fig. 2, some parts being broken away. Fig. 4 is a detail in section on the line $x^4 x^4$ of Fig. 3. Fig. 5 is a view of the machine in rear elevation with some parts removed and with some parts broken away; and Fig. 6 is a view similar to Fig. 5, but illustrating different positions of the parts.

The numeral 1 indicates a suitable case or cabinet which, as illustrated, is formed with display-compartments 2, with a mechanism-compartment 3, and with a drawer-compartment 4. Also, as shown, the display-compartments 2 are closed by a removable door 5, having a glass pane 6. The mechanism-compartment 3 is closed by a removable door 7, and the compartment 4 is provided with a drawer 8 for purposes which will presently appear.

Extended vertically within the compartment 3 is a magazine 9, which is adapted to contain a plurality of checks or tickets z , placed in a stack one on top of the other. The bottom of the magazine 9 terminates above the bottom of the compartment 3 a distance approxi-

mately equal to the thickness of one of the checks z , and the bottom check is adapted to be discharged out from under the stack and from the magazine through a slot 10, cut in one side of the case 1, as best shown in Fig. 6. 55

Within the compartment 3, rigidly secured to the bottom thereof, is a rectangular bearing-frame 11, and rigidly secured to the bottom of said compartment is a channel-like guide 12, in which works a sliding check-ejector 13, the end of which is adapted to work under the magazine and to force the lower check z out through the slot 10. (See Fig. 6.)

A plunger 14, which is mounted to slide horizontally and parallel to the ejector 13, is 65 connected to said ejector by an arm 15. A spring 16, attached to the bearing-frame 11 and to a short arm 17 on the plunger 14, yielding draws said plunger and said ejector 13 to their extreme positions toward the right with respect to Figs. 5 and 6. The numeral 18 indicates cushioning-washers, of rubber or leather, which are loosely placed on the plunger 14. The arm 17 at its upper end is pronged or notched and straddles a flange 11^a of the bearing-frame 11, thereby holding the plunger 14 against rotation. 70 75

An operating plunger or bolt 19, which at its outer end is shown as provided with a operating-knob 20, works through one side 80 of the case 1 and through one end of the bearing-frame 11 and is rigidly attached to a head 21, which in turn is mounted to slide on the plunger 14, and is formed with a depending leg 22, that straddles a flange 11^b of the frame 85 11 and is further guided thereby. The leg 22 is preferably formed with a stop-lug 22^a, which engages with a lug 11^c of the flange 11^b to limit the movement of the head 21 and operating-bolt 19 toward the left with respect 90 to Figs. 5 and 6 and toward the right with respect to Fig. 3. A coiled spring 23, attached at one end to the frame 11 and at its other end to a projection 21^b of the head 21, yielding draws the said head and the said plunger 95 19 to their extreme normal positions toward the right with respect to Figs. 5 and 6 and toward the left with respect to Fig. 3.

Projecting horizontally from the frame 11 and toward the left with respect to Fig. 3 is 100

a rigidly-secured ratchet-bar 24. Pivoted to the front face of the plunger-head 21 (see Fig. 3) is a combined lock-pawl and coin-grapple 25, the pawl end of which is normally held just above and out of engagement with the teeth of the ratchet-bar 24 by means of a spring 26, shown as secured at one end of said head 21. The pawl 25 has but slight movement, such movement being limited by a slot-and-pin connection 27 between the same and the said head 21. The short upturned end of the pawl 25 (see Figs. 3 and 4) is notched to receive the edge of the coin y , with a lip 25^a projecting outward thereof.

15 For coöperation with the short notched end of the pawl 25 to receive and hold the coin is an adjustable coin-grapple in the form of a short pinching-lever 28, pivoted to the head 21. This grapple member 28 at its free end is 20 subject to an adjusting-screw 29, that works through a lug 30 on the head 21.

Normally the head 21 and parts movable therewith stand in the positions indicated by dotted lines in Fig. 3 and by full lines in Fig. 25 5. The deposited coin is adapted to be delivered to the grapple members on the head 21 when the said head is in normal position by an inclined coin-delivery spout 31, which opens through one side of the case 1, is rigidly 30 secured thereto, and has its lower end terminated, as best shown in Figs. 3 and 5, in position to deliver the coin to the said grapping members 25 and 28, as already stated.

35 The numeral 32 indicates a cam-flange, which is formed on or rigidly secured to the frame 11 and extends in horizontal position for engagement with the upper portion of the coin which is carried by the head 21.

40 The numeral 33 indicates a catch-hopper, which is located in position to receive the coins dropped from the head 21 and to deliver the same through the bottom of the compartment 3 into the drawer 8.

45 The coin deposited in the spout 31 will be dropped against the upturned short end of the pawl 25 and against the upper end of the grapple-lever 28 and will be caught and held thereby, as already described. Under its own weight and the force of momentum the coin 50 caught as just described will wedge itself between the lever 28 and the upturned end of the pawl 25 and will throw the free end of said pawl downward into action on the teeth of the ratchet-bar 24. Hence when the bolt 55 or plunger 19 and its head 21 are moved toward the right with respect to Fig. 3 or toward the left with respect to Figs. 5 and 6 the said pawl 25 will catch on the teeth of said ratchet-bar and will hold said head 21 and 60 bolt 19 against return movements as long as the coin y is held as above stated. When the plunger 19 and head 21 are moved toward the right with respect to Fig. 3, the coin y , which is carried thereby, will be thrown against the 65 driving-stem 17^a on the lug 17 of the sliding

bolt or plunger 14 and the said bolt, together with the ejector-slide 13, will be moved toward the right with respect to Fig. 3 and toward the left with respect to Fig. 6, thereby ejecting one of the checks z , as shown in the 70 latter-noted figure. When the plunger 19 and head 21 are moved toward the right with respect to Fig. 3 or toward the left with respect to Fig. 6 somewhat farther than shown in the said figures, the cam-flange 32 comes 75 into action on the coin y (see Fig. 4) and will force the same laterally out from between the upturned end of the pawl 25 and the upper end of the grapple-lever 28 and causes the said coin to be dropped into the hopper 33, and thereby release the pawl 25 from the ratchet-bar 24 and permit the plunger 19 and head 21 to be thrown back to normal positions by the spring 23. The spring 16 serves to throw the plunger 14 and ejector 13 back to normal 80 positions as soon as the coin y is forced laterally out of engagement with the driving-stem 17^a.

85 From the foregoing description it is evident that the check-ejector cannot be operated unless a coin has been deposited between the 90 grapple elements carried by the head 21, and it is further evident that movement having been imparted to the said head and to the check-ejector said parts cannot be returned to normal positions until after the coin last 95 deposited has been forced from an operative position, thereby making it impossible to again operate the check-ejector without depositing another coin. The grapple member or lever 28 is made adjustable, so as to set the device to catch coins of different sizes and denominations, it being of course understood that the coin should drop substantially to predetermined distance between the coin-engaging 100 ends of the members 25 and 28.

105 The machine above described is capable of being used in a great many different ways. It may, for instance, be used to dispense or deliver checks marked with numbers or other characters which entitle the purchasers to any one of certain articles or of the kind of articles contained in the display-compartments 2. This machine may also be found serviceable for many other purposes, such as selling checks of determined value entitling the person securing them to drinks at a soda-water fountain or elsewhere or for selling tickets generally.

110 From what has been said it will be understood that the machine described is capable of modification within the scope of my invention as herein set forth and claimed.

115 What I claim, and desire to secure by Letters Patent of the United States, is as follows:

1. In a machine of the character described, 120 the combination with a magazine for articles to be delivered from the machine, of an ejector for delivering the articles from said magazine, a reciprocating plunger for operating said ejector, a relatively fixed rack, a pawl 125

130

carried by said plunger, with one end in position for action on the teeth of said rack, but normally held out of action thereon, the other end of said pawl serving as a coin-grapple, a coöperating coin-grapple carried by said plunger adapted to receive the coin, and the said pawl-grapple being thrown into action on said ratchet-bar by a deposited coin, a driver carried by said ejector, and positioned in the path of movement of a coin held by said grapples, of means for forcing said coins from said grapples, under movement of said plunger; and means for delivering the coin to the said grapples, substantially as described.

2. In a machine of the character described, the combination with a magazine for the checks or tickets, of a reciprocating check-ejector, a sliding plunger connected to reciprocate with said ejector, a spring acting on said plunger and on said ejector, to retract the latter, a reciprocating operating-plunger having a head at its inner end, a relatively fixed ratchet-bar,

a pawl pivoted to said plunger-head, with one end in position for action on the teeth of said ratchet-bar, but normally held out of action thereon, the other end of said pawl serving as a coin-grapple, a coöperating coin-grapple on said plunger-head, the said two grapples adapted to receive the coin, and the said pawl-grapple being thrown into action on the said ratchet-bar by a deposited coin, a driver carried by said ejector-plunger, and positioned in the path of movement of the coin held by said grapples, and a cam-flange in the path of movement of the coin for forcing the same out from between said grapples, substantially as described.

In testimony whereof I affix my signature in presence of two witnesses.

MARTIN WARNE.
